COMBINED AIR PUMP AND CUSHION

James J. Sunday, Detroit, Mich., assignor to
Minno-Life Corporation, Detroit, Mich., a corporation of Michigan

Application June 22, 1951, Serial No. 233,017

5 Claims. (Cl. 230—160)

1

This invention relates to air cushions for use in automobiles, row boats, on piers or other places by fishermen. The air cushion has the double utility of affording a comfortable seat cushion and acting as an air pump to aerate the water in a minnow pail.

Experienced fishermen know that one of the troubles a fisherman experiences is the dying of minnows in the minnow pail due to the exhaustion of the oxygen in the water because of so many minnows in such a small amount of water. This is hard to prevent if one has to transmit the minnow pail and minnows over distances in a motor car.

When carrying the minnows in a pail in a boat, the water can be changed by pouring it out through a perforated cover and then lowering the bucket with the perforated cover below the water level in the lake or river. This is a difficult and troublesome job requiring the fisherman or guide to stand up in the boat with the possibility of upsetting it and often spilling water in the boat. Furthermore sometimes the cover comes loose in pouring out the water and all the minnows are lost.

My combined air pump and cushion aerates the water in the pail by simply getting off the cushion and sitting down on the cushion again.

Referring to the drawings:

Fig. 1 is a vertical section of one end of a row boat and of the minnow pail, showing my cushion and the lower part of a man in elevation.

Fig. 2 is a vertical section through the cushion showing also a part of the hose for leading to the minnow pail. The section is taken on the line 2—2 of Fig. 3.

Figs. 3 and 4 are sections taken on the corresponding section lines of Fig. 2.

Fig. 5 is a bottom elevation of the cushion and pump.

Fig. 6 is a fragmentary perspective of the bottom of the cushion showing the air inlet valve.

1 may be the seat of a row boat, automobile, or other vehicle. The rubber air cushion and pump is designated 2. This comprises a bowl 3 molded of rubber or other air impervious flexible plastic or other material. The bottom 4 will be similarly made and the bottom and the top and sides (the bowl) can be vulcanized together at the turned out flanges which form, when vulcanized, the single flange 5 appearing in the drawings. This forms what I call in the claims the "air reservoir." Perhaps the whole cushion can be molded as one piece.

The bottom 4 is provided with peripheral supporting ribs 6 and radial supporting ribs 7. The

2

peripheral ribs 6 are interrupted at 8 and 9 to allow air into this sector which contains the air inlet valve 10 provided with stem 11. This stem projects into a hub 12 supported in opening 13 by radial ribs or spokes 14 which unite with a peripheral rib or rim 15 around the opening 13 which has the notches 16 to let the air pass. Valve 10 is a thin rubber disk which overlaps the opening 13 and also the bases of the rib 15.

10 A coiled spring 17 between the top and bottom walls tends to keep the cushion extended and inflated. The side of the bowl part of the cushion has a teat 18. This takes and grips a small piece of tube 19 and the rubber tube 20 fits over the outer end of this. The rubber tube has a valve 21 interposed in this air line leading to the minnow bucket 22.

The spring is centered in circular rib like bosses 23 in the bottom and 24 in the top wall. 20 The bowl part of the cushion has reinforcing radial ribs 25 on the inside.

25 The air is easily pumped into the water in the pail by a man sitting down on the seat. When he rises, air forces the flexible disk valve 10 open and fills the cushion. When he sits down again, the check valve closes and air is forced out the teat and through the tube into the bucket. This may be done as many times as is judged necessary.

30 What I claim is:

1. An air seat cushion and aerating device comprising a bowl member having top and side walls formed of a flexible but self-supporting, air impervious, rubber sheet material, said cushion also having a substantially flat bottom wall formed of a flexible self-supporting, air impervious, rubber sheet material, spring means within said cushion acting between said top and bottom walls to normally maintain said cushion in an expanded condition, said bottom wall having on its lower face a peripheral rib and a plurality of radial ribs for elevating said bottom wall from a supporting surface on which the cushion is positioned, said peripheral rib serving to support the outer peripheral portions of said bottom wall and said radial ribs serving to support the portion of said bottom wall spaced inwardly of the outer peripheral edge thereof, said cushion having an air outlet, said bottom wall being provided with an air inlet opening, a check valve controlling said air inlet opening, said peripheral rib having one or more openings therein for permitting air to flow to said air inlet opening when the cushion is positioned on a supporting surface.

2. The combination set forth in claim 1 where-

in said top wall is provided on the inner face thereof with a plurality of reinforcing ribs which serve to enhance the self-supporting nature of said top wall.

3. The combination set forth in claim 1 where-
in said bottom wall is provided on the lower sur-
face thereof with a rib extending circumferential-
ly around the edge of said air inlet opening and
including a plurality of radial ribs extending
across said opening and connected with said cir-
cumferential rib, said last mentioned radial ribs
intersecting within the area defined by said air
inlet opening to form a hub, said check valve com-
prising a flexible rubber disc within said cushion
overlying said air inlet opening, and means con-
necting a portion of said disc with said hub.

4. The combination set forth in claim 3 where-
in said hub is provided with an axial through
opening, said disc having a stem engaged within
said axial opening in said hub.

5. An air seat cushion and aerating device com-
prising a bowl member having top and side walls
formed of a flexible but self-supporting, air im-
pervious, rubber sheet material, said cushion also
having a substantially flat bottom wall formed of
a flexible self-supporting, air impervious, rubber
sheet material, spring means within said cushion
acting between said top and bottom walls to nor-
mally maintain said cushion in an expanded con-
dition, said bottom wall having on its lower face
a peripheral rib and a plurality of transversely

extending ribs which intersect each other and
connect with said peripheral rib to divide the
lower face of said bottom wall into a plurality of
adjacently positioned sections separated from one
another by said ribs, said air cushion having an
air outlet and said bottom wall having an air in-
let opening, a check valve controlling said air
inlet opening, said air inlet opening being located
on said bottom wall within the extent of one of
said sections, the section of said bottom wall in
which said air inlet opening is disposed being
defined along one side thereof by a portion of
said peripheral rib having openings therein to
permit air to pass into said section and to said
valve when the cushion is positioned on a sup-
porting surface.
